CLAIM

The ornamental design for a charging stand, as shown and described.

DESCRIPTION

FIG. 1 is a perspective view of a first embodiment for a charging stand showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front perspective view thereof;

FIG. 9 is a perspective view of a second embodiment for a charging stand showing our new design;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof; and,

FIG. 16 is a front perspective view thereof.

The broken lines and the grayed-out regions represent features which form no part of the claimed design.

1 Claim, 16 Drawing Sheets
